TOY CARRIER FOR A CHILD'S DOLL OR THE LIKE

Elizabeth Graham Johnson, Rose Bay, New South Wales,
Australia

Application February 21, 1955, Serial No. 34,606

Claims priority, application Australia November 18, 1954

Term of patent 14 years

(Cl. D34—22)

FIG. 1.

FIG. 2.

Fig. 1 is a front perspective view of a toy carrier for a child's doll or the like showing my new design; and
Fig. 2 is a rear perspective view thereof.

I claim:

The ornamental design for a toy carrier for a child's doll or the like, substantially as shown.
